(57) **CLAIM**

The ornamental design for an electronic device, as shown and described.

DESCRIPTION

FIG. 1 is a top, front perspective view of an electronic device showing our new design;

FIG. 2 is bottom, front perspective view thereof;

FIG. 3 is a bottom, rear perspective view thereof;

FIG. 4 is a top, rear perspective view thereof;

FIG. 5 is a top view thereof;

FIG. 6 is a right side view thereof;

FIG. 7 is a bottom view thereof;

FIG. 8 is a left side view thereof;

FIG. 9 is a front view thereof; and,

FIG. 10 is a rear view thereof.

The broken lines in the drawing illustrate portions of the electronic device that form no part of the claimed design.

The shade lines on the surface of the electronic device indicate contour and not surface decoration.

The gray shading on a portion of the electronic device represents a metallic-looking surface.
